UNITED STATES PATENT OFFICE.

HAROLD P. DONLE, OF MERIDEN, CONNECTICUT.

RECTIFIER.

1,420,824.

Specification of Letters Patent. Patented June 27, 1922.

Application filed May 31, 1921. Serial No. 474,006.

To all whom it may concern:

Be it known that I, HAROLD P. DONLE, a citizen of the United States of America, residing at Meriden, Connecticut, have invented a new and useful Rectifier, of which the following is a specification.

The main object of my invention is to provide a simple, inexpensive but efficient type of rectifier for alternating currents.

10 In its preferred form the invention utilizes two cold electrodes within a vacuum tube. I make use of the fact that negative particles tending to leave an electrode or move away from its vicinity will move in lines substantially at right angles to the electrode surface. By suitably forming and locating the electrodes I have found that I can secure predominating one-way transmission and consequently rectification.

20 I have been able to obtain rectification in this way with several different constructions.

Figure 1 illustrates one form of apparatus involving my invention for half-wave rectification, the tube being shown in longitudinal section and the circuit being shown diagrammatically;

Figs. 2 and 3 are longitudinal sectional views of tubes with other forms of electrodes; and

Fig. 4 is a view similar to Fig. 1 but showing a tube and circuit for full-wave rectification.

The tube 6 may be of the ordinary type 35 of glass tube exhausted or evacuated to a suitable degree. I have found a pressure of approximately one millimeter of mercury to be satisfactory. An inert gas may be present at a corresponding pressure.

40 The electrodes 7 and 8 are of suitable metal, such as molybdenum, tungsten or other durable metal. I provide the electrode 8 with a flange 9, so that it is in the form of a cup, which has a hole 10 in the center of

45 its active surface. The other electrode may have a flange 11. These cups are placed with their faces so close together as to prevent or minimize ionization between the adjacent surfaces.

50 Fig. 1 shows a circuit with an A. C. generator 12 and a transformer 13. When the tube is connected as shown in this figure, a pulsating direct current flows in the work circuit. When this type of tube is in opera-

tion the ionization glow very nearly fills the 55 cathode cup 8. This glow is separated from the walls of the cathode by a dark space. Projecting from the anode through the hole 10 a small conical column of very intense light will be seen, and it is impossible, while 60 watching the operation, to distinguish the exact junction between the general glow throughout the interior of the cathode and this brilliant column emanating from the anode.

65 My theory of operation is that when the pierced electrode 8 is subjected to the negative potential of the A. C. wave to be rectified, thus making the solid electrode 7 the anode, all negative particles within the cathode 8 will be repelled from it to the center and literally forced through the hole to the anode 7. The particles moving from the cathode to the anode under normal conditions in a tube of approximately 1 $\frac{1}{4}$ inches 70 internal diameter will collide with gas molecules after they have reached a distance of about $\frac{3}{16}$ ths of an inch from the inside wall of the cup 8. The electrons resulting from this collision will pass axially of the tube 80 and through the hole 10 to the anode 7. The small bright cone-shaped discharge marks the position of very violent collisions, as the particles are moving through a comparatively restricted zone and all collisions there- 75 in take place with great violence.

85 When the potential of the current to be rectified reverses and the electrode 8 becomes positive the few electrons which come through the hole 10 find a weak field tending to draw them in all directions distributed over a large curved area, and they do not get up sufficient velocity for ionization.

90 Other electrons pass directly to the electrode 8, which is now positive, without causing ionization. Consequently, no current or only small current passes through the tube in this inverse direction.

95 For high voltages the electrodes should be as close together as possible, to eliminate a 100 two-way discharge between the faces. The electrodes may be initially placed or adjusted farther apart for lower voltages where the electrons will necessarily be required to traverse a longer distance in order to absorb sufficient energy to ionize the gaseous atoms. With higher potentials the electrons start out at high velocities and acquire suf-

ficient energy a very short distance from their starting points. In such cases the electrodes must be very close together.

In the construction of Fig. 2 the electrode 7' is shown solid, and electrode 8' is shown with a recess 10'. In this case the space between the adjacent faces of the electrodes is less than the free mean path required for ionization.

10 In the form shown in Fig. 3 the negative electrode 7'' is in the form of a cylinder or tube with one end sufficiently close to the anode to bring it within the dark space. The field from the anode extends axially of the 15 cathode in the recessed chamber 10''.

The tube and circuit of Fig. 4 is for complete or full wave rectification. The central tubular electrode 8^a constitutes the cathode, and the discs 7^a the anodes at opposite ends, 20 so as to use both sides of the A. C. wave.

In any case the electrodes should be of sufficient area to avoid overheating under the conditions for which the tube is designed.

I have found that the tube of Fig. 4 may 25 also be used for doubling the frequency of the impressed A. C. by providing a transformer in the work circuit.

The theory of operation which I have set forth as to Fig. 1 also applies to the other 30 forms shown. For instance, when the electrode 8' of Fig. 2 becomes negative, electrons are vigorously repelled from the metal to the center of the orifice 10, and thence axially toward the anode 7. In this movement they set up extensive ionization and consequently the device becomes a good conductor for the half-wave applying negative potential to the electrode 8'. On the other hand, when 7' is negatively charged, electrons repelled from 7' to the adjacent face of 8' travel so short a distance that ionization is negligible or absent; such of them as are propelled into the orifice 10' are not strongly attracted by 8' in any given 45 direction and cause little, if any, ionization. Consequently, for the half-wave which makes 7' (instantaneously) a cathode, the conductivity of the tube is negligible.

In the same way the action of Fig. 3 50 may be understood. The chamber 10'' is the active locus of ionization when the electrode 8'' is charged negatively, but little or no ionization is produced when electrode 7'' is negative. The cylinder 8'' may be placed close to or in contact with the glass 55 wall of the tube 6, since the inside of the cathode 8'' is most highly active in producing the effects of rectification which I have discovered. When it is supported freely in 60 the interior of the tube, the few electrons which may be outside the tubular electrode seem to play no substantial part in the operation of the device.

In Fig. 4 the two anodes 7^a operate alternately, the electrons from or near the cath-

ode 8^a being driven continually toward the center of the tube and alternately along the axis to whichever of the anodes is the more strongly charged positively. I have found this form of tube to be somewhat more 70 efficient than two single-anode tubes connected in a similar divided-transformer circuit, perhaps because some ionization is residual and carries over from one alternation to the next, and because each anode as 75 it becomes negatively charged aids in repelling the electrons toward the other.

In order to determine whether or not the electrodes in any particular device are properly located i. e. so closely spaced as 80 to minimize ionization in the inverse current flow direction, one may apply across the terminals of the device under test a direct current potential of the order of the alternating current potential to be rectified. 85 When the electrode 7 is made positive the tube will ionize as above described and considerable current will flow. However, when electrode 7 is made negative there will be substantially no ionization and negligible 90 or no current will flow, if the spacing between the electrodes is sufficiently small for proper operation of my rectifier.

I claim:

1. In a rectifier, a vacuum tube, two electrodes within said tube and having their adjacent faces arranged so close together as to minimize ionization between them under one direction of applied potential, one of said electrodes having an orifice providing 100 an ionizing path along its axis.

2. In a rectifier, a vacuum tube, two electrodes within said tube and having their adjacent faces of unequal area and arranged so close together as to minimize ionization 105 between them under one direction of applied potential, one of said electrodes having a passage to provide an ionizing path along its axis.

3. In a rectifier, a vacuum tube, a hollow 110 cathode and an anode arranged opposite thereto at a distance less than the mean free path required for ionization under electromotive forces impressed in one direction.

4. In a rectifier a tube, two electrodes 115 within said tube with their adjacent faces spaced apart a distance less than the mean free path required for ionization in one direction, the cathode having an ionizing passage.

5. In a rectifier, a tube, two electrodes within said tube with their adjacent faces spaced apart a distance small enough to minimize ionization under electromotive forces impressed in one direction, the cathode having a passage through the face adjacent said anode, and the anode having a plane face. 125

6. In a rectifier, a plane faced electrode, a cylindrical electrode arranged with one end 130

adjacent the other electrode and having a central ionizing space.

7. In a rectifier, two plane electrodes and a tube electrode between them having an ionizing passage.

8. In a rectifier, a tube having a transversely disposed anode and a longitudinally extending cathode with an unobstructed central zone of ionization.

10. 9. In a rectifier, a tube, a cylindrical

cathode mounted therein and having an axial ionizing space, and an anode extending substantially at right angles to the axis of said cathode.

10. In a rectifier, a tube, a tubular 15 cathode mounted therein having a longitudinally extending ionizing space, and anodes extending transversely of said tube at opposite ends of said cathode.

HAROLD P. DONLE.
